United States Patent

Des. 241,212
Patented Aug. 31, 1976

241,212

DESK

Ronald R. Hodges, Grandville, and Jack Hockenberry,
Grand Rapids, Mich., assignors to Steelcase Inc., Grand
Rapids, Mich.

Filed May 22, 1973, Ser. No. 362,853

Term of patent 14 years
The term of this patent subsequent to Feb. 25, 1989,
has been disclaimed

Int. Cl. D6—04

U.S. Cl. D6—161

FIG. 1

→ VII

FIG. 2

→ VIII

FIG. 3

FIG. 7

FIG. 4

FIG. 5

FIG. 6

FIG. 8

FIG. 9

FIG. 10

FIG. 1 is a perspective view of a desk embodying the design of the invention;

FIG. 2 is a front elevational view of the desk;

FIG. 3 is an end elevational view of the desk;

FIG. 4 is a rear elevational view of the desk;

FIG. 5 is a generally rear perspective view of the desk;

FIG. 6 is a top plan view of the desk;

FIG. 7 is a cross-sectional view taken generally along plane VII-VII of FIG. 2;

FIG. 8 is a front elevational view of an alternative embodiment desk embodying the design of the invention, the drawer arrangement being different from the desk shown in the previous figures;

FIG. 9 is a perspective view of an alternative embodiment desk embodying the design of the invention, the desk top being generally flush with the tops of the end panels, rather than as shown in the preceding figures; and

FIG. 10 is a perspective view of an alternative embodiment desk embodying the design of the invention, the desk top being sloped forwardly slightly from rear to front.

We claim:

The ornamental design for a desk, substantially as shown.
